COMMUNICATION APPARATUS

Richard H. Campbell, Racine, Wis., assignor to
 Webster Electric Company, Racine, Wis., a corporation of Wisconsin

Application June 29, 1937, Serial No. 150,951

22 Claims. (CL 179—39)

This invention relates to communication apparatus, and particularly to telephonic communication apparatus in which suitable voice receiving and transmitting means, such as dynamic loud speakers of the type comprising a permanent magnet, are employed for the dual function of receiving and transmitting, the fluctuations in electrical current created in the receiver being amplified by a suitable amplifier.

According to the present invention I provide a dominant or central instrument at a location hereinafter termed a central station, and one or more secondary instruments located at suitable positions remote therefrom and hereinafter termed remote stations. I provide a switch at the central station and bias it to a normal position conditioning the system for communication from the remote stations to the central station. When it is desired to communicate in the opposite direction, that is from the central station to the remote stations, this switch must be operated to another position and when in that position the remote stations are unable to communicate with the central station. Each of the remote stations is provided with a switch occupying a normal position conditioning the remote station for the reception of speech. When this switch is moved to its other position, the remote station is conditioned from the transmission of speech from it to the central station, provided, of course, that the aforementioned switch at the central station is in its normal position.

As will be fully understood from the following description of preferred embodiments of the invention, the switches effect the connection of the input and output ends of the amplifier to the transmitting and receiving loud speaker, respectively.

One of the objects of the invention is to provide an apparatus of this type in which a central station and a plurality of remote stations is provided, each of said remote stations being adapted for direct conversation with the central station without communicating to the other remote stations.

A further object of the invention is to provide communicating apparatus in which the central station may talk and be talked to, by a selected one of the plurality of remote stations, each of said stations being normally adapted to talk to the central station when desired.

A further object of the invention is to provide communicating apparatus of this type in which a central station is normally adapted to talk to all of the plurality of remote stations, each of

which is adapted to be switched to non-receiving and transmitting condition.

A further object of the invention is to provide a communicating system of this type in which a central station is switched to communicate with any one of a plurality of remote stations so that conversation can be carried on exclusively therebetween, said central station being dominant so that it can be preferentially connected to the input end of the amplifier at the will of the central operator.

A further object of the present invention is to provide a communicating system of this type in which any of the remote stations may cause a regenerative signal at the central station.

Other objects, advantages and capabilities of the invention will appear from the following description of preferred embodiments thereof, taken in conjunction with the accompanying drawings, in which:

Fig. 1 is a diagrammatic view of one embodiment of my invention;

Fig. 2 is a diagrammatic view of a modified embodiment of my invention;

Fig. 3 is a diagrammatic view of a further modified embodiment of my invention, and

Fig. 4 is a diagrammatic view of still another modified embodiment of my invention.

Referring first to Fig. 1, the reference numeral 10 designates voice receiving and transmitting means, such as a dynamic loud speaker unit of the type employing a permanent magnet and a voice coil suspended in the field thereof, located at a station from which the communication system is to be controlled. This station may be aptly termed either a master or central station, and hereinafter will be referred to as a central station.

Speaker units 11, similar in all respects to units 10, are located at one or more remote stations between which and the control station it is desired to communicate.

The fluctuations in current produced in the units, when acting as receivers, are amplified by an amplifier 12 of any suitable type comprising one or more stages of amplification. It may be provided with volume control as well as a switch for connecting it to a suitable source of power, but since these elements, as well as the amplifier itself, may be of any well known construction, they are not illustrated or described in great detail herein. For present purposes it is sufficient to state that one terminal of both the input and output of the amplifier are connected to a common grounded conductor 13 that extends

from the central station to all remote stations, as will appear hereinafter.

A selectively operable switch 14 is provided at the central station for connecting the speaker unit 10 thereto to either the output or input of the amplifier, and at the same time either condition the remote speaker units 11 for connection to the input of the amplifier by selectively operable switches 15 at the remote stations, or 10 directly connect the remote speaker units to the output of the amplifier. The switch 14 is biased by suitable means, such as a spring, to a position in which the speaker unit 10 is connected to the output and the units 11 are conditioned for connection to the input by switches 15, whereby any of the remote stations may communicate with the central station.

The switch 14 is a double pole double throw switch having its first switch blade 16 connected by a conductor 17 to the output of the amplifier, and its other switch blade 18 connected by a conductor 19 to the input of the amplifier. The switch is biased into a position in which the blade 16 engages one of a pair of interconnected contacts 20 and the blade 18 engages a contact 21. When the switch is operated from its normal position, the switch blade 16 engages a contact 22 and the switch blade 18 engages another of the interconnected contacts 20.

When the switch 14 is in its normal position, as illustrated in Fig. 1, the speaker unit 10 is connected to the output of the amplifier by means of a conductor 23 connecting one terminal of the voice coil 24 to the interconnected contacts 20, the other terminal of the voice coil being connected to the common conductor 13. In its normal position the switch 14 also conditions the remote speakers for connection to the input through a conductor 25 leading from contact 21 to the switch 15 of a first remote station and having a plurality of branch conductors 26 and 27 leading to other remote stations. The switches 15 are all biased to an open position from which they may be operated to engage contacts 28 connected directly to the voice coils 29 of the remote speaker units. Whenever a switch 15 is operated into engagement with the contact 28 and the switch 14 is in its normal position, a voice coil 29 is connected directly across the input of the amplifier through a circuit including the common conductor 13 and branch conductors 13' leading from the latter to the voice coils of the speaker units at remote stations.

When the switch 14 is operated to its displaced position, the speaker unit 10 at the central station is connected to the input of the amplifier through switch blade 18 and conductor 19 and the remote speakers are connected directly to the output of the amplifier through conductor 17, switch blade 16 and a conductor 30 leading from contact 22 to the junction of the various contacts 28 with their respective voice coils.

From the above detailed description of the invention, it may be seen that whenever the switch 14 at the central station is in its normal position, any of the remote stations may communicate with the central station upon operation of the switch 15 at the remote station into engagement with the contact 28. Upon the operation of switch 15 in this manner, the voice coil associated with the speaker unit at the remote station is connected across the input of the amplifier through the switch, conductor 25, switch blade 18, and conductor 19. The amplified signals are impressed upon the speaker 10 at the central sta-

tion through a circuit including the conductor 17, switch 16, and conductor 23 leading to the voice coil 24.

After the remote station has communicated with or called the central station, the operator at the latter station may manipulate switch 14 to its displaced position and communicate with the remote station. At this time the unit 10 at the central station is connected across the input of the amplifier through conductor 19, switch blade 18, and conductor 23, and the speakers 11 are connected to the output of the amplifier through conductor 17, switch blade 16 and conductor 30. Whenever the switch 14 is operated into its displaced position, the remote stations cannot communicate with the central station because actuation of the switch 15 into engagement with contact 28 has no effect inasmuch as conductor 25 is not actively associated with the amplifier in the displaced position of switch 14. Thus, it may be seen that the direction of communication is under the sole control of the operator at the central station.

The embodiment of the invention illustrated in Fig. 2 differs from that described above in that the remote stations are provided with control means whereby they may select only those messages which they desire to receive from the central station, and the central station is provided with selector means whereby it may communicate with any one or all of the remote stations.

The apparatus at the central station in the modification of Fig. 2 corresponds identically with that of the previously described embodiment, with the exception of the addition of a selector switch 31 which is placed in the common conductor 13. The selector switch has an arcuate contact 32 adapted in one position to connect the conductor 13 to all the branch conductors 13' leading to the various voice coils 29, and in other positions to engage either one or the other of the branch conductors 13'. In order to enable the remote stations to receive only desired messages, each station is provided with a switch 33 normally biased into engagement with a contact 34 connected to the previously described conductor 30 and adapted to be actuated into engagement with a contact 35 connected to the previously described conductor 25. The various contacts 34 and 35 are connected to the conductors 25 and 30 by branch conductors 36 and 37.

In the operation of the embodiment illustrated in Fig. 2, when the switch 14 is in its normal position and the selector switch 31 connecting the common conductor 13 to all the branch conductors 13', the system is conditioned for communication from the remote stations to the central station by operation of switches 33 into engagement with contacts 35. Upon the described operation of any one of the switches 33, the speaker unit 11, associated therewith, is connected directly across the input of the amplifier just as in the previously described modification. In response to a call from any remote station, the operator at the central station may operate the switch 14 to its displaced position, thereby connecting the output of the amplifier to conductor 30. Then, if the operator at the remote station wishes to listen to a communication from the central station, he releases the switch 33, which is then returned into engagement with contact 34, thus connecting the speaker across the output of the amplifier. If the operator at any station does not wish to listen to a particular communication from the central station, it is only neces-

sary for him to disengage switch 38 from contact 34 and thereby prevent the transmission of the message to the voice coil of the speaker at that station.

In view of the fact that the central station apparatus is the same as in the modification of Fig. 1, the direction of communication is under the sole control of the operator at the central station. Furthermore, if the operator at the central station desires to communicate with only one of the remote stations, he may do so by actuating the selector switch 31 to a position in which the common conductor 13 is connected with the branch conductor 13' leading to the particular remote station with which he wishes to communicate.

The embodiment of the invention shown in Fig. 3 differs from the embodiment shown in Fig. 1 primarily in the provision of a different type of selector switch 40 at the central station. The selector switch of this embodiment differs from the selector switch in the embodiment of Fig. 2 in that it is so constructed and arranged in the circuit that the operator at the central station may communicate with any one or all of a number of remote stations, exceeding two in number, and likewise may cut off communication from all remote stations if he so desires. The selector switch 40 consists of a substantially circular contact segment 41 and a contact bar 42 extending centrally from within the segment 41 to a point outside its periphery. The contacts 41 and 42 may be supported in the position illustrated by suitable means, such as an insulating bar 43. The ungrounded sides of the various voice coils 29 are connected to individual contacts adapted to be engaged by the arcuate segment 41 and also by the contact bar 42. When the selector switch is in the position illustrated, the common conductor 13 is connected to all the branch conductors 13' through the contact bar 42 and a conductor 43 connecting the latter to the arcuate segment 41, which is in contact with all of the conductors 13'. Consequently, with the selector switch in the illustrated position, any one of the remote stations may communicate with the central station, and the central station likewise may communicate with all the remote stations when the switch 14 is actuated to its displaced position.

Whenever the operator at the central station wishes to communicate with a particular remote station, he actuates switch 40 to connect the contact bar with the conductor 13' leading to the station with which he desires to communicate. At this time the common conductor 13 is connected to the desired conductor 13' through the contact bar and the other conductors 13' are disconnected from the common conductor by reason of the fact that the arcuate segment 41 is connected to the common conductor only when the contact bar is in the position illustrated. When the selector switch is actuated in this manner, only the station selected can communicate with the central station and consequently the other remote stations cannot listen to the communication between the central station and the selected remote station.

When the operator wishes to cut off communication with all remote stations, he is able to do so simply by operating switch 40 into a position in which the contact bar 42 is not in engagement with any of the branch conductors 13' or the conductor 43.

The embodiment of the invention shown in Fig. 4 differs from that shown in Fig. 3 in the pro-

vision of means for creating a regenerated signal at the central station whenever a switch 15 at the remote station is closed to connect the speaker unit thereto to the input of the amplifier. The regenerated signal is created by coupling the output of the amplifier to the input whenever the switch 15 is closed with the switch 14 at the central station in its normal position. This coupling is provided by means of a circuit extending from the interconnected contacts 20 to conductor 30 and comprising a conductor 45, a current limiting resistance 46, and a switch 47. The switch is biased to its open position, but is adapted to be closed under certain hereinafter described conditions by a cam 48 operatively connected by a shaft 49 for simultaneous operation with the selector switch 40. If desired the shaft 49 may be biased to a normal position corresponding to that illustrated in Fig. 4 by a spiral spring 50, so that the system is normally conditioned for calling by the remote stations.

To enable the operator at the central station simultaneously to communicate with all the remote stations, as in the previously described modifications, the selector switch 40 is provided with a stationary contact 44 adapted to be engaged by the contact bar 42 in one position thereof. When the contact bar is in engagement with contact 44 the conductor 13 is connected to all of the remote stations through the contact bar 42, conductor 43 and contact segment 41. In this position of the selector switch, the switch 47 is open and consequently the operator at the central station may communicate with all of the remote stations. Likewise, any of the remote stations may communicate with the central station when the selector switch is in this position and the switch 14 is in its normal position.

When the operator at the central station desires to communicate with any particular remote station, he actuates the selector switch 40 to bring the contact bar 42 into engagement with the particular branch conductor 13' leading to the desired remote station. This operation of the selector switch results in the opening of switch 47, thereby rendering impossible the creation of a regenerated signal in the speaker at the central station. The operator then depresses switch 14 to its displaced position, thereby connecting the voice coil 24 of speaker 10 to the input of the amplifier and connecting the output of the amplifier to the remote speakers 11. The circuit is, however, completed only through one of these coils, that one being the one associated with the particular branch conductor 13' connected to the conductor 13 by the contact bar 42. The operator at the remote station called may reply when the switch 14 returns to its normal position and the operator closes the switch 15 at the remote station.

If the operator at one of the remote stations desires to call the central station, the selector switch 40 being in its normal position corresponding to the position illustrated in Fig. 4 and to which it is automatically returned, the operator at the remote station merely closes his switch 15 a predetermined number of times to indicate which station is calling. When he closes this switch a circuit is completed between the output and input of the amplifier 12, the circuit extending from the output to the input through conductor 17, switch blade 16, contacts 20, conductor 45, resistance 46, switch 47 in its closed position, conductor 30, switch 15, conductor 25, switch blade 18, and conductor 19. The result of

this connection is a feed back of energy from the output to the input, and the amplifier regenerates to produce a howl in the speaker 10. The code signal thus emitted by a predetermined sequence 5 of howls informs the operator at the central station that a certain remote station desires to communicate with him. The operator at the central station thereupon throws the selector switch 40 to communicate with that particular station and thereby private communication can be maintained in the same manner as in the embodiment 10 shown in Fig. 3. It should be noted that the operators at the other remote stations are unable to cut into the conversation, either to 15 listen thereto or interrupt it.

It is to be noted that while I have shown only a comparatively few stations in each of the embodiments of the invention illustrated, it must be understood that I have no intention to be 20 limited thereto, since the number of remote stations may be multiplied to any extent desired.

Although the invention has been disclosed with the specific details of preferred embodiments thereof, it must be understood that such details 25 are not intended to be limitative of the invention, except in so far as set forth in the accompanying claims.

Having thus described my invention, what I claim as new and desire to secure by Letters 30 Patent of the United States is:

1. A multiple station intercommunication system, including in combination, voice receiving and transmitting means comprising a loudspeaker adapted to function as a microphone and a loudspeaker at each station, an amplifier, a pair of inter-station conductors adapted selectively to be connected to the input and output 35 of the amplifier, selectively operable means at a first station operable to a first position for connecting the voice receiving and transmitting means thereat to the output and the first conductor to the input of said amplifier and to a second position for connecting the voice receiving and transmitting means to the input and the 40 second conductor to the output of said amplifier, and means at another of said stations for connecting the voice receiving and transmitting means thereat to the input of said amplifier through said first mentioned conductor and said 45 selectively operable means when the latter connects the voice receiving and transmitting means at the first station to the output of said amplifier.

2. A multiple station communication system, 50 including in combination, a voice receiving and transmitting means comprising a loudspeaker adapted to function as a microphone and a loudspeaker at each station, an amplifier, a pair of interstation conductors adapted selectively to be connected to the input and the output of the 55 amplifier, means at a first station operable to a first position for connecting the voice receiving and transmitting means thereat to the output and one of said pair of conductors to the input of said amplifier and simultaneously disconnecting the other conductor from said amplifier, and to a second position for connecting the voice receiving and transmitting means to the input and the said other conductor to the output of the 60 amplifier, and simultaneously disconnecting said one conductor from the amplifier, said means including plural position switching means biased to said first-mentioned position, and means at another of said stations for connecting the voice receiving and transmitting means thereat to the 65

input of said amplifier through said one conductor and said switching means when the latter is in its first-mentioned position.

3. A multiple station communicating system, including in combination, a speaker adapted to function as a microphone and loudspeaker at each station, an amplifier, means at said first station for selectively connecting the speaker thereto to the output and input of the amplifier, said means including a multi-pole plural-position 10 switch biased to a normal position in which the speaker is connected to the output of the amplifier and operable to connect said speaker to the input and the speaker at the second station to the output, and means including a selectively operable switch at the second station for connecting the speaker thereto to the input of said amplifier through the first mentioned switch when the latter is in its normal position. 15

4. An intercommunicating system, including in combination, a central station, a plurality of stations remote therefrom, loudspeaker units adapted to function as microphones and loudspeakers at each station, an amplifier, means including a master switch at the central station operable into a first position for connecting the speaker at the central station to the input and the remote speakers directly to the output of the amplifier and operable into a second position for connecting the speaker at the central station to 20 the output and conditioning the remote speakers for connection to the input of the amplifier, means normally biasing said master switch to its second position, and switches at each of said 25 remote stations for completing the connection of the respective speakers to the input of the 30 amplifier. 35

5. A communicating apparatus comprising a central loudspeaker, a plurality of remotely located loudspeakers adapted to function as microphones and loudspeakers connected in parallel, a switch associated with each remote loudspeaker, an amplifier, a main switch adjacent the central loudspeaker adapted in one position to connect the central loudspeaker to the input of the 40 amplifier and the other loudspeakers directly to the output of the amplifier, and in another position to connect the central loudspeaker to the output and the remote switches to the input, and means normally holding the main switch in said 45 last position whereby each remote speaker may be connected by its switch at will to the input of the 50 amplifier when the main switch is in its normal position.

6. A communicating apparatus comprising a 55 pair of remotely located loudspeakers adapted to function as microphones and loudspeakers, an amplifier, a multi-pole plural-position switch adjacent one speaker having one of its poles connected to the input of the amplifier and another 60 pole connected to the output of the amplifier, means normally holding said switch in one position, contact means adapted to be engaged by the last mentioned pole in the normal position of the switch and by the first mentioned pole in 65 the actuated position of the switch, a conductor connecting said contact means to the adjacent loudspeaker, contact means engaged by the first mentioned pole in the normal position of the switch, a conductor extending from the last mentioned contact means to the remote speaker, a switch for connecting said last mentioned conductor to the remote speaker, contact means engaged by the second mentioned pole when displaced from normal position, and a conductor 70

connecting said last mentioned contact means directly to the remote speaker.

7. An intercommunicating system, including in combination, a central station, a remote station, 5 loudspeaker units adapted to function as microphones and loudspeakers at each station, an amplifier, a pair of interstation conductors adapted selectively to be connected to the amplifier means including a master switch at the central station 10 operable into a first position for connecting the speaker thereat to the output and conditioning the other speaker for connection to the input of the amplifier by connection of a first interstation conductor to the input of the amplifier 15 and operable into a second position for connecting the speaker thereat to the input and conditioning the other speaker for connection to the output of the amplifier by connection of a second interstation conductor to the output of the 20 amplifier, a switch at the remote station operable into a first position to complete the connection of the speaker thereat to the output through said second interstation conductor and a second position to complete the connection of the speaker 25 to the input of the amplifier through said first interstation conductor, and means biasing both of said switches to their first positions whereby the system is conditioned for initiation of communication from either station by operation of 30 the switch thereat to its second position.

8. An intercommunicating system including in combination, a central station, a plurality of remote stations, loudspeaker units adapted to function as microphones and loudspeakers at 35 each station, an amplifier, a pair of interstation conductors adapted selectively to be connected to the amplifier means including a master switch at the central station operable into a first position for connecting the speaker unit thereat to 40 the output and conditioning the remote speakers for connection to the input of the amplifier by connection of a first interstation conductor to the input of the amplifier, and operable into a second position for connecting the speaker thereat to 45 the input and conditioning the remote speakers for connection to the output of the amplifier by connection of the second interstation conductor to the output of the amplifier, a switch at each remote station operable into a first position to 50 complete the connection of the speaker thereat to the output through said second interstation conductor and to a second position to complete the connection of the speaker thereat to the input of the amplifier through said first interstation 55 conductor, means biasing the master and all the remote switches to their first mentioned positions whereby the system is conditioned for initiation of communication from any station by operation of the switch thereat to its second position.

60 9. A multiple station intercommunicating system, including in combination, loudspeaker units adapted to function as microphones and loudspeakers at each station, an amplifier, control means at one of said stations for connecting the speaker thereat to the output of the amplifier and for conditioning the speaker at a second station for connection to the input of the amplifier, control means at the second station operable to complete the connection of the speaker thereat to 65 the input of the amplifier, and means for creating an audible signal at the first station rendered effective upon operation of said last mentioned means to complete the connection.

70 10. A multiple station intercommunicating system, including in combination, loudspeaker units

adapted to function as microphones and loudspeakers at each station, an amplifier, control means at a central station normally connecting the speaker thereat to the output of the amplifier and conditioning the remaining speakers for connection to the input of the amplifier, control means at each of said remaining stations operable to complete the connection of the speaker thereat to the input of the amplifier, and means for creating a regenerated signal in the speaker 10 at the central station rendered effective upon operation of any of said last mentioned control means to complete said connection.

11. A multiple station intercommunicating system, including in combination, loudspeaker units 15 adapted to function as microphones and loudspeakers at each station, an amplifier, control means at a central station adapted to connect the speaker thereat to the output of the amplifier and condition the remaining speakers for connection to the input of the amplifier, control means at each of said remaining stations operable to complete the connection of the speakers thereat to the input of the amplifier, means for creating an audible signal in the speaker at the 20 central station upon operation of any of said last mentioned control means to complete said connection, and other control means at the central station for rendering said last mentioned means 25 inoperative.

12. A multiple station intercommunicating system, including in combination, loudspeaker units adapted to function as microphones and loudspeakers at each station, an amplifier, control means at a central station normally connecting 35 the speaker thereat to the output of the amplifier and conditioning the remaining speakers for connection to the input of the amplifier, control means at each of said remaining stations operable to complete the connection of the speakers 40 thereat to the input of the amplifier, means for creating an audible signal in the speaker at the central station upon operation of any of said last mentioned control means to complete said connection, selector means at the central station 45 normally connecting all said remaining stations to said central station and operable to connect any one of said remaining stations to said central station, and means operable simultaneously with operation of said selector means from its normal 50 position to render said signal creating means inoperative.

13. An intercommunicating system, including in combination, a central station, a remote station, a loudspeaker adapted to function as a microphone and loudspeaker at each station, an amplifier at the central station, means including a multi-pole plural position switch biased to a normal position to connect the speaker thereat to the output of the amplifier and operable to connect said speaker to the input and condition the remote speaker for connection to the output, means including a normally open switch at the remote station for connecting the speaker thereat to the input of the amplifier through the first mentioned switch when the latter is in its normal position, and means including a circuit comprising a resistance element and switch at the central station for connecting the output to the input to produce a regenerated signal in the speaker at the central station whenever the switch at the remote station is operated to connect the speaker thereat to the input.

14. A communicating apparatus comprising a pair of remotely located loudspeakers adapted to

function as microphones and loudspeakers, an amplifier, a double pole double throw switch adjacent one speaker having one of its switch blades connected to the input of the amplifier and the other switch blade connected to the output of the amplifier, means normally holding the switch in one position, contact means adapted to be engaged by the second mentioned switch blade in the normal position of the switch and by the first mentioned switch blade in the actuated position of the switch, a conductor connecting said contact means to the adjacent loudspeaker, contact means engaged by the second mentioned switch blade when displaced from normal position, a conductor connecting said last mentioned contact means to the remote speaker, a circuit including a current limiting resistor and a switch located near the main speaker whereby said first mentioned contact means may be connected to the second mentioned contact means, contact means engaged by the first mentioned switch blade in the normal position of the switch, a conductor extending from the last said contact means to the remote speaker, and a switch for connecting the last mentioned conductor to the speaker.

15. A multiple station communicating system, including in combination, voice receiving and transmitting means comprising a loudspeaker adapted to function as a microphone and a loudspeaker at each station, an amplifier, selectively operable means at a first station for connecting the voice receiving and transmitting means thereat to the output and input of said amplifier, means at the remaining stations for connecting the voice receiving and transmitting means thereat to the input of said amplifier through said selectively operable means when the latter is operated to connect the voice receiving and transmitting means at the first station to the output of said amplifier, and single control means at the first station for selectively controlling the connection of the speakers at the remaining stations to the amplifier, whereby the first station can communicate with any or all the remaining stations.

16. A multiple station communication system, including in combination, loudspeaker units adapted to function as microphones and loudspeakers at each station, an amplifier at a first station, selectively operable means at said first station for connecting the speaker thereto to the output and input of said amplifier, control means at each of the remaining stations operable to connect the speakers thereat to the input of said amplifier through the selectively operable means when the latter is operated to connect the speaker at the first station to the output of the amplifier, means including a switch at the first station operable to a position wherein it cooperates with the selectively operable means and control means to connect the output to the input of the amplifier for producing by regeneration an audible signal in the speaker at the first station, and a selector switch mechanically connected for simultaneous operation with the last mentioned switch, said selector switch being operable to two positions in which all the said remaining speakers are connected to the amplifier and in one of which positions the switch mechanically connected thereto is in circuit making position, whereby the control means at remaining stations may be operated to produce a regenerative signal at the first station, and in the other of which positions the said switch is in circuit breaking position, whereby the first

station may call simultaneously all the remaining stations, said switch being operable to other positions to connect any one of said remaining speakers to the amplifier to the exclusion of the others, at which positions the switch mechanically connected thereto is in circuit breaking position. 5

17. In an inter-communicating system, the combination including a plurality of stations, voice receiving and transmitting means comprising a loudspeaker adapted to function as a microphone and a loudspeaker at each station, an amplifier, a circuit comprising two inter-station conductors connecting the voice receiving and transmitting means at the stations, control means at a first station for selectively connecting the voice receiving and transmitting means thereat to said conductors through said amplifier, control means at the remaining stations for connecting the voice receiving and transmitting means thereat to said conductors, said conductors and control means being so arranged that only one of said conductors is connected to the amplifier when communication is established in either direction. 10 15 20 25

18. A multiple station inter-communicating system including, in combination, voice receiving and transmitting means at each station, an amplifier, selectively operable means at a first station for connecting the voice receiving and transmitting means thereat to said amplifier, selectively operable means at the remaining stations for connecting the voice receiving and transmitting means thereat to the amplifier, and means rendered effective upon operation of the last mentioned means into a predetermined position to couple the output to the input of the amplifier for creating an audible signal at the first station. 30 35

19. In an inter-communicating system of the type including a central station and a plurality of remote stations, the combination including voice receiving and transmitting means at each station, a communication direction control switch at the central station, and a single selector switch at the central station so constructed and arranged 40 45 with respect to the remote stations that communication may be established between the central station and any one or all the remote stations.

20. A multiple station inter-communicating system comprising a loudspeaker adapted to function as a microphone and a loudspeaker including, in combination, voice receiving and transmitting means at each station, an amplifier, selectively operable means at a first station for connecting the voice receiving and transmitting means thereat to the amplifier, selectively operable means at the remaining stations for connecting the voice receiving and transmitting means thereat to the amplifier, and a rotary selector switch at the first station so constructed 50 55 60 and arranged with respect to the said remaining stations that any one or all of the remaining stations may be connected to said amplifier.

21. In combination, voice receiving and transmitting means of the type adapted to function 65 both as a microphone and a loudspeaker, an amplifier, a communication circuit comprising two conductors, and control means for said voice receiving and transmitting means, amplifier and conductors, said control means being so constructed and arranged that it can be manipulated 70 to connect said voice receiving and transmitting means to the input and one of said conductors to the output of the amplifier or to connect said voice receiving and transmitting means to the 75

output and the other of said conductors to the input of the amplifier, the remaining conductor in each case being disconnected from the amplifier.

22. In an intercommunicating system, the combination including an amplifier, a plurality of remotely located stations connected by a communication circuit including a common return leading to the amplifier, voice receiving and transmitting means at each station, a switch for

controlling the connections of the amplifier, voice receiving and transmitting means and communication circuit, and a selector switch located in the common return circuit so constructed and arranged with respect to the various stations that communication may be established between a station at which the selector switch is located and selected stations remote therefrom.

R. H. CAMPBELL.

CERTIFICATE OF CORRECTION.

Patent No. 2,162,368.

June 13, 1939.

RICHARD H. CAMPBELL.

It is hereby certified that error appears in the printed specification of the above numbered patent requiring correction as follows: Page 6, second column, lines 50 and 51, claim 20, strike out the words "comprising a loudspeaker adapted to function as a microphone and a loudspeaker" and insert the same after "means" in line 53, same claim; and that the said Letters Patent should be read with this correction therein that the same may conform to the record of the case in the Patent Office.

Signed and sealed this 5th day of September, A. D. 1939.

Henry Van Arsdale,
